BATTERY-CHARGING SYSTEM.

Application filed April 17, 1922. Serial No. 553,892.

This invention relates to battery charging systems in which an internal-combustion engine drives a dynamo as a generator to charge a storage battery, from which current may be taken to operate the dynamo as a motor to crank the engine, and in which current is used to furnish electrical ignition for the engine.

Devices such as reverse current relays have been used for connecting the battery and dynamo for starting purposes by a manual operation, said devices automatically maintaining the charging circuit to the battery when the engine becomes self-operative and attains a certain speed, said circuit being broken upon discharge of the battery to the generator. Ignition relays or similar devices actuated upon the attainment of a certain battery voltage to stop battery charging by stopping the engine have been used. Means have been employed for decreasing the resistance of the ignition circuit while cranking the engine so as to obtain sufficient current from the battery for igniting the explosive charge.

It is an object to provide simple and efficient means for controlling the ignition relay so as to render the same inoperative when it is desired to overcharge the battery.

It is a further object of the present invention to provide a simple and efficient controller including the engine starting control, reverse current relay, and switch mechanism for controlling the ignition relay to render the same inoperative in case it is desired to overcharge the battery.

A further object is to embody in a single controller the engine starting control, reverse current relay, ignition relay controller, and a controller for the ignition resistance which becomes inoperative when the starting control lever is released.

A further object is to provide a control for the ignition relay or other device for stopping the engine which will be rendered inoperative automatically when the battery charging circuit is automatically broken.

A further object is to provide an improved voltage relay by means of which the contacts in the controlled circuit will not flutter as the critical voltage is reached, but will remain in good contact making position until such a voltage is obtained in the relay that the contacts shall be suddenly opened.

Further objects and advantages of the

present invention will be apparent from the following description, reference being had to the accompanying drawings, wherein a preferred form of one embodiment of the present invention is clearly shown.

In the drawings:

Fig. 1 is a diagrammatic side elevation of an internal-combustion engine directly connected with the dynamo which is shown partly in section, together with a wiring diagram including a diagrammatic side elevation of the controlling device included in the present invention;

Fig. 2 is a fragmentary side view of the improved relay.

In the drawings, 20 designates an internal-combustion engine driving a dynamo 21 which is directly connected with the engine. Dynamo 21 includes an armature 22, commutator 23, brushes 24 and 25, and field pole pieces 26 and 27, the dynamo is provided with a shunt winding 28 connected across the brushes 24 and 25.

Ignition is furnished for the internal-combustion engine by means of an ignition coil 30 which includes a primary winding 31 connected with a timer 32, the other end of the primary winding 31 is connected with a terminal 33. The secondary winding 35 is connected at one end with a spark plug 36 and grounded at the other end upon the engine 20.

40 designates a battery the positive side of which is connected to a terminal 41 and the negative side with an ammeter 42.

The controller 50 will now be described. This controller includes a frame 51 of magnetic material supporting a magnetic core 52 and an armature post 53. A pivotally mounted armature 55 is mounted upon the armature post 53. A magnetic circuit is formed by members 52, 51, 53, and 55, with a gap between the armature 55 and the core 52. Core 52 carries series winding 60, one end being connected with the terminal 61, the other with terminal 65 by line 108. Core 52 also carries a shunt winding 68, one end being connected at terminal 59, the other with a terminal post 64 by line 58. Terminal post 65 carries a resilient conductor 67, which is provided with a contact 68. Contact 68 is arranged to engage with terminal post 64. A non-conducting roller 71, which is mounted upon an arm 72 formed integrally with the armature 55, engages the re-

silient conductor 67 when the armature 55 is moved upwardly thereby bringing contact 68 into engagement with post 64.

A terminal post 77 carries a resilient conductor 78 carrying a contact 79 which is arranged to engage with a contact 80 connected to terminal post 81. A controller lever 82, pivotally mounted on the armature post 53, carries a roller 83 which is arranged to engage with the resilient conductor 78 for the purpose of bringing contacts 79 and 80 into engagement. Lever 82 is provided with a projecting tongue 84 which is adapted to engage with the underside of block 85 of non-magnetic material, which is mounted upon the underside of the armature 55 and which prevents a magnetic circuit being directly formed between armature 55 and lever 82 and permits an independent movement of said lever after the armature has been attracted by the core 52. The lever 82 and the armature 55 are mounted upon a rod 87, supported by the armature post 53. A resilient conductor 88 is mounted upon a terminal post 89 carried by the frame 51 and is located within the path of movement of the resilient conductor 67 so as to be engaged thereby when the contacts 68 and 64 are closed.

30 A resilient conductor 90 is mounted upon a terminal post 91 and is provided with a groove 92 which cooperates with a tongue 93 carried by a lever 94 which is pivotally mounted upon the rod 87 of the armature post 53. An arm 95 of the lever 94 lies in the path of movement of the armature 55 for the purpose to be described.

Terminal posts 64, 65, 81, and 91, which have been described, are all mounted upon the frame 51 but are insulated therefrom while the armature post 53 and terminal post 89 are grounded thereon.

A relay 100 is provided with a winding 101, one end of which is connected with terminal 102, the other end is connected by line 104 to terminal 103. An armature 105, pivotally mounted at 106 and normally held in contact with contact 107 by a spring 109, is controlled by the winding 101 of the relay 100.

The operation of the device is as follows:

To start the engine lever 82 is pulled upwardly causing the roller 71 to effect the engagement of contacts 68 and 64 thereby bringing into effect the cranking circuit which includes line 125 leading from the positive side of the battery 40 to the fuse terminal 41, fuse 110, terminal 112, line 113 to the switch terminal 61. From switch terminal 61 the circuit continues through the series windings 60 of the starting switch through line 108 to the switch terminal 65, resilient conductor 67, contact 68, terminal post 64, line 115, positive generator terminal 116, through the motor generator, termi-

nal 117, line 118 to terminal 119. From terminal 119 the current continues through line 120, terminal 103, line 121, terminal 59, line 122, ammeter 42, line 123 to the negative side of the battery.

At terminal 64 the current divides and a part passes through line 58 to the shunt winding 63 of the starting switch and connects with terminal 59 which in turn is connected to the negative side of the battery. In this manner during the cranking operation current will flow through the winding 60 in such a manner as to operate differentially with respect to winding 63 so that magnetic flux created within the core 52 is insufficient to maintain the armature in circuit closing position.

The upward movement of lever 82 will cause the roller 83 to effect the engagement of contacts 79 and 80, thereby bringing into effect the ignition circuit while cranking. The ignition circuit while cranking consists of bar 160 which connects terminal 65 with terminal post 77, resilient conductor 78, contact 79, contact 80 on terminal post 81, line 127, terminal 33, primary windings 31 of the ignition coil 30, timer 32, line 129, terminal 130, contact 107, armature 105, terminal 106, wire 104 and terminal 103 at which point the ignition circuit re-unites with the cranking circuit and continues to the negative side of the battery 40.

The secondary ignition circuit comprises a secondary winding 35 of the ignition coil 30, grounded on the engine and connected to the spark plug 36.

After the engine has become self-operative it will drive the dynamo electric machine as a generator to charge the battery. The generator circuit comprises line 115 leading out from the positive terminal 116 of the generator, terminal post 64, contact 68, resilient conductor 67, terminal 65, line 108, series winding 60 of the starting switch, terminal 61, line 113, fuse terminal 112, fuse 110, terminal 41, line 125, to the positive side of the battery 40. The current continues through the battery to the line 123, ammeter 42, line 122, terminal 59, line 121, terminal 103, line 120, terminal 119, line 118 to negative terminal 117 of the generator. At terminal post 64, the current divides a portion thereof passes through line 58, shunt windings 63 of the starting switch to terminal 59 back to the negative side of the generator. Current will then flow through the windings 63 and 60 so as to operate cumulatively, thereby energizing the core 52 forming a magnetic circuit between the core 52, frame 51, armature post 53, armature 55, causing the armature 55 to be attracted to the core 52.

The attendant may then release lever 82 which will fall by force of gravity and will permit roller 83 to disengage resilient con-

tact 78 permitting contacts 79 and 80 to become separated. The ignition for the engine will then be furnished through the resilient contact 88, which is in contact with resilient conductor 67 when contacts 68 and 64 are in engagement. The current will then continue from the terminal post 89, line 140 through ignition resistance 141 to terminal 33, said terminal 33 being connected to the primary winding 31 of the ignition coil 30.

A work circuit to electrical translating devices branches from the positive terminal 112 and passes through a line 142, terminal 143, fuse 144, terminal 145, switch 146 to a positive terminal 147 on the positive side; and on the negative side of the work circuit the current passes through a negative terminal 148, switch 146, terminal 149, fuse 150 to the terminal 119.

At terminal 89, a portion of the current divides and passes from the frame 51 to the armature post 53, rod 87, arm 93, resilient contact 90, terminal post 91, line 151, terminal 102, winding 101 of the relay 100, wire 104, to terminal 103 where the current again unites with the negative side of the generator circuit and flows to negative generator terminal 117.

When the battery is being charged the resistance in the battery gradually increases and the charging current decreases accordingly with the result that the engine, operating at a lighter load, speeds up and thereby raises the charging voltage. The charging continues until the voltage across winding 101 energizes the relay sufficiently to overcome the resistance of a spring 109 thereby causing the armature 105 to be attracted, the winding 101 and spring 109 being so computed that the battery is fully charged when the armature 105 is attracted. When the armature 105 is attracted it will be separated from the contact 107, which will cause the ignition circuit to the engine to be broken and likewise stop the plant.

When the engine becomes inoperative and the generator ceases to generate, current will flow from the positive side of the battery to the controller terminal 61 through winding 60 in the opposite direction to that while generating. While at the same time current will be flowing through winding 63 oppositely from that of winding 60. The magnetic flux created by the winding 60 will then tend to balance the flux created by the winding 63, and the armature will then drop away from the core 52 permitting the disengagement of contacts 68 and 64 and the disengagement of resilient conductor 67 and resilient contact 88 and in this manner break the electrical connections between the battery and generator and also break the ignition circuit at the starting switch. The starting switch will then be in a position to again be manually operated.

It is often necessary to give the battery an equalization charge by overcharging same. In order to bring this equalization charge into effect the relay 100 must be cut out so that the ignition contact will not be broken after the battery has reached a predetermined charge. This is done by means of the lever 94 which when lifted will cause the arm 93 to become disengaged from the groove 92 of the resilient conductor 90, thereby breaking the circuit to the winding 101 of the relay 100. After the battery has received its equalization charge the attendant will manually stop the plant as by shutting off the engine fuel by means of throttle 200. Current will then flow through the windings 60 in one direction and through the winding 63 in the opposite direction, thereby causing the armature 55 to fall away from the core 52. The starting switch contacts will then become disengaged as was previously described.

While the armature 55 is moving downwardly the arm 95 of lever 94 will lie within the path of movement of the armature 55 and will be engaged thereby causing the arm 93 to slide upwardly upon the inclined surface of the resilient conductor 90 and slide within the groove 92 of said resilient conductor. After this operation has been brought into effect a connection is re-established in the relay circuit, whereby the relay 100 will again be brought into operation when the starting switch lever is again pulled upwardly to effect the connection between the battery and the generator. By causing the lever 94 to be automatically restored to circuit making position as shown in Fig. 1, it is not necessary for the attendant to pay attention to the position of this switch lever when starting the engine. Its normal position is such as to cause the ignition relay to be operative and as the lever 94 is much shorter and less accessible than lever 82 there is little likelihood of the attendant accidentally moving the lever 94 when reaching to take hold of lever 82.

The relay 100 includes a magnet core 162 and a frame 163 of magnetizable material carrying a pivot 164 which supports armature 105. The stationary contact 107 is carried by a bracket 165 supported by frame 163 but insulated therefrom said bracket being connected with terminal 130. Contact 107 cooperates with contact 167 carried by a leaf spring 168 attached adjacent one end by rivets 169 to armature 105. Spring 168 is preferably of non-magnetizable material so as to provide magnetic insulation between armature 105 and core 162, thereby to prevent "sticking" when magnet 101 is de-energized. Spring 168 is provided with a tongue 170 which extends down through a hole 185 in armature 105 and engages a reduced portion of pivot member 164 to pre-

vent the same from moving endwise. Spring 168 is provided with a hole through which a stud 172 extends. The stud is attached to armature 105 and is provided with a shoulder 173 for limiting the movement of blade 168 away from armature 105. Stud 172 is provided with an eye 174 for attachment to spring 109 which normally tends to maintain the armature separated from core 162.

The operation of the relay 100 is as follows:

Normally armature 105 is in a position such that the contacts 107 and 167 are closed, and the gap between the core 162 and armature 105 is the maximum so that there will be a space between the spring 168 and the shoulder 173 of stud 172. As the charge to the battery continues the resistance thereof increases and the voltage across the generator terminal and likewise in the coil 101 will increase whereby the magnetism of the relay will increase. When the battery is substantially fully charged, the magnetism at first will just about balance the spring 109. The armature 105 may quiver for an interval as the critical point is being approached but the contacts will not be separated because the shoulder 173 of stud 172 has not moved far enough to engage the spring blade 168. By the time the magnetism has increased to a degree where the armature takes the position shown in Fig. 2, the gap between the armature and core will have decreased to such an extent, that the rate of increase of magnetic pull far exceeds the rate of increase of spring pull and the armature will no longer quiver but will instantly move into full attracted position as shown in Fig. 9. Therefore it is seen that as certain current must pass through coil 101 before the contacts 107, 167 will be separated, and before this current is attained the contacts will remain together although the armature may quiver. Therefore it is apparent that a clean and quick break of the ignition circuit will be obtained.

By providing a positive stopping means for the engine, there is no chattering of the ignition circuit contacts which chattering would tend to decrease the speed of the engine and likewise the output of the generator with a possibility that the predetermined voltage will not be attained and the engine will remain operative.

While the form of mechanism herein shown and described constitutes a preferred embodiment of one form of the invention, it is to be understood that other forms might be adopted and various changes and alterations made in the shape, size, and proportion of the elements therein without departing from the spirit and scope of the invention.

What is claimed is as follows:

1. In a battery charging system, the com-

bination with an engine and a dynamo connected therewith; a battery charged by the dynamo; an engine ignition circuit including ignition apparatus and two switches in series with the battery; an engine control circuit including an electromagnet for controlling one of the ignition circuit switches and connected with the battery through the other ignition circuit switch; and means responsive to the stopping of the engine for disconnecting the battery from the dynamo and opening said other ignition switch for disconnecting the ignition apparatus and electromagnet from the battery.

2. In a battery charging system, the combination with an engine and a dynamo connected therewith; a battery charged by the dynamo; an engine ignition circuit including ignition apparatus and two switches in series with the battery; an engine control circuit including an electromagnet for controlling one of the ignition circuit switches and connected with the battery through the other ignition circuit switch; a manually operated switch for controlling the electromagnet; and means responsive to the discharge of current from the battery to the dynamo for disconnecting the battery from the dynamo and for opening said other ignition switch for disconnecting the ignition apparatus and electromagnet from the battery.

3. In a battery charging system, the combination with an internal combustion engine and a dynamo connected therewith; a storage battery charged by the dynamo; automatic means for stopping the engine when the battery has attained a certain charge; manual means for rendering the automatic engine-stopping means inoperative; other means for stopping the engine; and means responsive to the stopping of the engine for restoring the manual means to non-operating position.

4. In a battery charging system, the combination with an internal combustion engine and a dynamo connected therewith; a storage battery to be charged by said dynamo; automatic means for stopping said engine when the battery has attained a certain charge; automatic means for disconnecting the battery from the dynamo in case the engine stops; manual means for rendering said automatic engine stopping means inoperative; and other means for stopping the engine; said manual means being restored to inoperative position by the operation of said automatic battery disconnecting means.

5. In a battery charging system, the combination with an internal combustion engine and a dynamo connected therewith; a storage battery to be charged by said dynamo; ignition apparatus for the engine; automatic means for rendering the ignition inopera-

5 tive whereby to stop the engine when the battery has attained a certain charge; automatic means for disconnecting the battery from the dynamo in case the engine stops; 10 manual means for rendering said first automatic means inoperative; and other means for stopping the engine; said manual means being restored to inoperative position by the 15 operation of said automatic battery disconnecting means.

6. In a battery charging system, the combination with an internal combustion engine and a dynamo connected therewith; a storage battery to be charged by said dynamo; 15 ignition apparatus for the engine; an ignition relay responsive to battery voltage to render the ignition inoperative thereby to stop the engine when the battery has attained a certain charge; automatic means 20 for disconnecting the battery from the dynamo in case the engine stops; a manual controlled switch for disconnecting the ignition relay; and other means for stopping the engine; said switch being restored to circuit 25 closing position by the operation of said automatic battery disconnecting means.

7. In a battery charging system, the combination with an internal combustion engine and a dynamo connected therewith; a storage battery to be charged by said dynamo; ignition apparatus for the engine; an ignition relay responsive to battery voltage to render the ignition inoperative thereby to stop the engine when the battery has attained a certain charge; of a controller including a reverse current relay for automatically disconnecting the battery from the dynamo in case the engine stops, including manual means for holding said relay contacts closed so that the battery may discharge into the dynamo to operate the same as a cranking motor, and including manual means for rendering the ignition relay inoperative, said last manual means being restored to normal position by the operation of said reverse current relay in case the engine stops.

8. In a battery charging system, the combination with an engine and a dynamo connected therewith; a battery charged by the

dynamo; an engine ignition circuit including ignition apparatus and two switches in series with the battery; a switch connecting the battery and dynamo; an ignition control circuit including an electromagnet for opening one of the ignition switches and connected in circuit with the battery and the other ignition switch, and a manually operated switch for rendering said magnet inoperative; a movable member for closing said other ignition switch and the switch connecting the battery and dynamo; an electromagnet for maintaining the movable member in circuit closing position so long as the current delivered by the dynamo exceeds a certain value; and means for causing the manually operated switch in the ignition control circuit to be moved into non-operating position in response to the release of said movable member by said electromagnet.

9. In a battery charging system, the combination with an engine and a dynamo connected therewith; a battery charged by the dynamo; an engine ignition circuit including ignition apparatus and two switches in series with the battery, one ignition switch being normally open and the other normally closed; a switch connecting the battery and dynamo; an ignition control circuit including, in series with the battery, the normally open ignition switch, an electromagnet for opening the normally closed ignition switch, and a normally closed switch for opening the magnet circuit; a lever for closing the normally open ignition switch and the dynamo-to-battery switch; an electromagnet for maintaining the lever in circuit closing position until the output of the dynamo falls below a certain amount; and a lever for opening the normally closed switch in the ignition control circuit and having a part located in the path of movement of the first lever to be moved thereby into circuit closing position by the movement of the first lever to non-operating position.

In testimony whereof we hereto affix our signatures.

ERNEST DICKEY.

HENRY P. BRAEUTIGAM.
